RAILWAY CAR VESTIBULE DIAPHRAGM

Edward E. Whitmore, Chicago, Ill., assignor to
The Adlake Company, Chicago, Ill., a corpora-
tion of Illinois

Application April 23, 1937, Serial No. 138,612

4 Claims. (Cl. 105—18)

The present invention has to do with railway car vestibule diaphragms of the type in which the sides of the diaphragm are made of flexible material and are arranged in one or more accordions-like pleats. When a diaphragm of this type is used between adjoining railway cars, openings will ordinarily be formed between the lower edges of the pleated sides of the diaphragm and the ends of the overlapping foot plates, which openings are continually changing their size and shape with the weaving and turning movements of the cars. These openings sometimes become quite large, particularly when the cars are traveling around a curve, and it is entirely possible for a person in passing from one car to the other to fall and allow a leg, foot or hand to slip momentarily into one of these scissors-like openings, with likelihood of serious consequences.

The principal object of this invention is to provide a foot plate enclosure boot on the inner surface of each side of a diaphragm, which boot will effectively shield the floor opening at that side of the passageway without interfering in any way with the movements of either the foot plates or the diaphragm.

While the foregoing statement is indicative in a general way of the nature of the invention, other more specific objects and advantages will be apparent to those skilled in the art upon a full understanding of the construction, arrangement and operation of the new enclosure boot.

Two different embodiments of the invention are presented herein for the purpose of exemplification—one for a single pleat diaphragm and the other for a double pleat diaphragm—but it will of course be appreciated that the invention is susceptible of embodiment in other structurally modified forms coming equally within the scope of the appended claims.

In the accompanying drawings:

Fig. 1 is an end view of a single pleat diaphragm, with the inner surfaces of the sides thereof equipped with the boots which form the subject matter of this invention;

Fig. 2 is a side view of the diaphragm;

Fig. 3 is an enlarged vertical section through the lower end of one of the sides of the diaphragm, taken on the line 3—3 of Fig. 2, showing both the regular foot and the extra foot or boot;

Fig. 4 is an enlarged horizontal section through one side of the diaphragm, taken on the line 4—4

of Fig. 1, showing that side of the diaphragm expanded;

Fig. 5 is a similar enlarged section, showing the same side of the diaphragm contracted; and

Figs. 6, 7, 8 and 9 are views, corresponding respectively to Figs. 1, 2, 4 and 5, showing the invention incorporated in a double pleat dia-

phragm. The diaphragm shown in Figs. 1 to 5 inclusive is made of any suitable flexible material, such as heavy belting canvas. One end of the diaphragm is attached to one end 10 of the car, about the arched passageway therein, and the other end is attached to a face plate 11. The top 12 of the diaphragm and the sides 13 there-
of are arranged in a single pleat which permits contraction and expansion of the diaphragm upon movement of the face plate toward and away from the end of the car. The lower ends of the sides 13 of the diaphragm terminate in 20
feet 14, preferably made of a softer material, such as chrome leather, which may be trimmed off flush with the foot plates 15 and 16 which are secured respectively to the end 10 of the car and the face plate 11.

Secured to the inner surfaces of the lower ends of the sides 13 of the diaphragm, above the regular feet 14, are closure boots 17 which terminate at their lower edges in supplemental feet 18. The boots 17, with their feet 18, are ar-
ranged at an inclination to the sides 13 of the diaphragm and merge upwardly into the latter, with the feet 18 spaced inwardly from the feet 14 at all times regardless of whether the dia-
phragm is contracted or expanded. The ex-
panded position is shown in Fig. 4, while the contracted position is shown in Fig. 5. It will
be observed in these views that the boots 17, with their feet 18, are bowed or pleated at all
times in conformity with the sides 13 of the dia-
phragm, with the center bends in the feet 18
projecting far enough into the passageway to
overlie the openings 19 which develop between
the edges of the foot plates. The upper edges
of the boots 17 are stitched or otherwise se-
curely attached, preferably along horizontal
lines 20, to the inner surfaces of the sides 13 of
the diaphragm. The lower edges of the feet 18,
like the feet 14, are preferably cut off flush with
the foot plates.

In the embodiment shown in Figs. 6 to 9 in-
clusive a diaphragm is shown which has two
pleats 21 and 22. The foot plate closure boots
23 used with this type of diaphragm are differ-
ent in that they are mounted in the crevices 55

24 which are present between the two pleats. The boots 23 merge upwardly at an inclination into the adjacent parts 25 of the pleats and form supplemental pleats which overlie the openings 26 between the foot plates.

5 In this type of diaphragm a metal frame 27 is employed between the end 28 of the car and the face plate 29. This metal frame, to which the adjacent portions 25 of the diaphragm are attached, preferably terminates a substantial distance above the bottom of the diaphragm, at 30, which increases the flexibility of the sides of the diaphragm near the bottom thereof and facilitates the application and expansion and contraction 10 of the gusset-like boots 24.

15 I claim:

1. A diaphragm for application to a railway car vestibule having a passageway with overlapping foot plates and openings at the side edges 20 of the plates, which diaphragm is of the type in which the sides are made of flexible material and are vertically pleated in one or more folds to permit of an accordion-like expansion and contraction, said diaphragm being provided on the 25 inner surfaces of the lower ends of the sides with supplemental feet, which feet are set inwardly from the regular feet on the lower edges of the sides, whereby to provide closures for said foot plate openings.

30 2. A diaphragm for application to a railway car vestibule having a passageway with overlapping foot plates and openings at the side edges of the plates, which diaphragm is of the type in which the sides are made of flexible material and 35 are vertically pleated in one or more folds to permit of an accordion-like expansion and contraction, said diaphragm being provided on the inner surfaces of the lower ends of the sides with

supplemental feet which are set inwardly from the regular feet on the lower ends of the sides and merge upwardly into the sides above such regular feet, whereby to provide closures for said foot plate openings.

5

3. A diaphragm for application to a railway car vestibule having a passageway with overlapping foot plates and openings at the side edges of the plates, which diaphragm is of the type in which the sides are made of flexible material 10 and are vertically pleated in one or more folds to permit of an accordion-like expansion and contraction, said diaphragm being of the pleated type, provided on the inner surfaces of the lower ends of the sides with supplemental gusset-like 15 feet which are set inwardly from the regular feet on the lower ends of the sides and merge upwardly into the sides above such regular feet, with the supplemental feet pleated in conformity with the sides, whereby to provide closures for 20 said foot plate openings.

4. A diaphragm for application to a railway car vestibule having a passageway with overlapping foot plates and openings at the side edges of the plates, which diaphragm is of the type in 25 which the sides are made of flexible material and are vertically pleated in one or more folds to permit of an accordion-like expansion and contraction, said diaphragm being provided with inwardly protruding boots of flexible material 30 attached to the lower portions of the pleated sides of the diaphragm, with the center portions of the boots bowed inwardly away from the opposed portions of the sides of the diaphragm in both the expanded and contracted positions of 35 the sides, whereby to fully cover said foot plate openings.

EDWARD E. WHITMORE
